DOOR CLOSER AND CHECK

Louis L. Schacht, New York, N. Y.

Application August 27, 1947, Serial No. 770,896

12 Claims. (Cl. 16—55)

1
This invention relates to a spring-closing mechanism for doors, particularly of the type having a pivot post extending downwardly from the lower edge of the door and an axially aligned pivot post extending upwardly from its upper edge, the pivot posts being pivotally mounted in the floor and the upper lintel of the door opening, respectively. The mechanism serves to maintain the door in closed position, and is additionally provided with means for checking or slowing the rapidity of closing.

The closing and checking mechanism may be located in the floor (or lintel), or it may be contained within the door itself, either at its lower or upper portion. For facility in illustration, the closing and checking mechanism of this invention is shown set in the floor and operating upon the door through the floor pivot post, although it will be understood that it may be applied to any of the alternate locations enumerated.

The improved closing and checking mechanism may be applied to "double-acting" doors, i. e., which open both inwardly and outwardly, substantially 90° in each direction so that the total extent of turning is substantially 180°, or it may be applied to "single-acting" doors, i. e., which open in only one direction, either inwardly or outwardly, substantially 90° in each case. The invention is shown and described as applied to both double-acting and single-acting door.

The principal object of the invention is to provide a door closing mechanism (or a door closing and checking mechanism) which will exert the greatest (spring) pressure upon the door when it is in its closed position. The "closed" position of a single-acting door will be at one limit of its 90° angle of opening; the "closed" position of a double-acting door will be at the mid-point, or 90° point, of its 180° angle of opening. In door fixtures as heretofore commonly made, a spring or other member is tensioned, compressed, or otherwise altered in a manner to build up a force counteracting the manual force applied to open the door, tending to turning the door in the opposite sense, i. e., towards its closed position. This "closing" force is increased, from a minimum value in the closed position, substantially directly with the manual opening movement imparted to the door, reaching a maximum value when in the fully opened position. In the common door fixture, therefore, the minimum closing pressure is applied when the door is in its closed position.

In the improved door closing mechanism of this invention, on the other hand, the greatest "closing" pressure is exerted by the mechanism,

not when the door is in open position, but when it is in closed position, i. e., in the position of the door when the "closing" force is most wanted to maintain the door closed. This feature of maximum application of closing pressure in the closed position of the door is especially desirous in doors of the "latchless" type, notably glass doors. Doors of this type are maintained in closed position—i. e., when not positively locked or bolted—only by the pressure exerted by the door closing mechanism. By reason of the fact that the minimum closing pressure is exerted when the door is in closed position, doors, especially of the latchless type, implemented with the common closing mechanism, will rattle when subjected to slight gusts of wind or changes in air pressure. This is especially noticeable in the case of outside or entrance doors. This wind rattling had become a serious problem in connection with modern all-glass lobby or store doors. The improved door closing mechanism of this invention entirely eliminates wind rattling for the reasons stated above.

This problem of rattling of latchless and other types of doors cannot be overcome by merely increasing the tension or compression of the closing element. This is because, if sufficient tension or compression is applied to the door when in its closed position in order to hold it against rattling, the amount of force required to open the door, especially to its fully opened position, will be too great for the average person to apply in opening the door. This is, of course, due to the fact that in the ordinary door closing fixture, the tension or compression of the closing element is increased proportionally to the extent of door opening, reaching a maximum in the full opened position. In the improved device of this invention, on the other hand, the maximum force required to maintain the door against rattling can be imposed on the device; as pointed out above, as the door is opened, this tension or compression is decreased, rather than increased, so that there is not present in the improved device the objection that an increased force will be required to open the door.

For the attainment of the foregoing and such other objects as may appear or be pointed out herein, I have shown a preferred embodiment of my invention in the accompanying drawing,

50 wherein:

Fig. 1 is a top view of the improved door closing and checking mechanism as applied to a double-acting door, shown in closed position;

Fig. 2 is a front sectional elevation taken substantially on the line 2—2 of Fig. 1;

Fig. 3 is a top view of the left portion, Fig. 1, of the mechanism, showing the parts when the door is opened counterclockwise about 45°;

Fig. 4 is a top view similar to Fig. 3 but showing the parts when the door is fully opened (90°) clockwise; and

Fig. 5 is a top view of the improved closing and checking mechanism as applied to a single-acting door, the door being in closed position.

As mentioned in the statement of invention, the improved door closing (and checking) mechanism of this invention will be shown for disposition in the floor or threshold, although it may be placed in the other locations enumerated above. The mechanism is contained within a shallow casing 9, which is embedded in the floor with the upper surface thereof at the floor level. The upper surface of casing 9, although shown open in the drawing, will be, of course, closed by a plate (not shown) which is apertured for the lower pivot post 2 of the door. As explained in the statement of invention, this type of door is pivotally mounted by a lower pivot post, such as 2, supported in a bearing in the threshold plate or floor and an axially aligned pivot post (not shown) in the door lintel, so that the door—designated 1A in Fig. 3 and 1B in Fig. 4—may turn on said pivot posts. As best shown in Fig. 2, pivot post or door spindle 2 has a reduced portion 3 at its lower end which is mounted in a ball bearing 4 secured to a plate 5 fastened to the floor of casing 9.

Considering first the double-acting door of Figs. 1 to 4, there are provided a spring 10 which is acted upon, as will be explained, when the door is opened in a clockwise sense (as viewed in the figures)—and which, for this reason, will be referred to as the "clockwise" spring—and a similar spring 10' which is acted upon when the door is opened in the opposite or counterclockwise sense. The two springs 10, 10' are similar, so that the ensuing description of the clockwise spring 10 applies equally to the "counterclockwise" spring 10', the parts of which are designated similarly except that the reference characters are primed.

Clockwise spring 10 is a helical compression spring disposed between a transverse plate 8 of casing or housing 9 and a washer 21 and nut 22 at the threaded right end of a rod 20. Rod 20 is slidable in an aperture 8a in casing plate 8 and has a flattened portion 20f at its left end, see Fig. 2, so that the upper surface of flat 20f may abut the under surface of a transverse bar 30, subsequently described, and so that the under surface of flat 20f may abut the upper surface of a lower connecting link 24, also subsequently described. That is, the left end of rod 20 and the right ends of a pair of parallel links 23, 24, which are disposed vertically one above the other, Fig. 2, are articulated together and to a transverse bar 30. This triple articulation is achieved by a pin 31. As best shown in Fig. 1, the rod 20' and links 23', 24' of the counterclockwise spring 10' are articulated to one end of transverse bar 30 at pin 31' while the rod 20 and links 23, 24 of the clockwise spring 10 are articulated to the other end of transverse bar 30 at pin 31.

Between distal ends of links 23, 24 is rotatably mounted a roller 25. The roller 25 associated with the "clockwise" links 23, 24 and spring 10 and the roller 25' associated with the "counterclockwise" links 23', 24' and spring 10' both cooperate with a cam plate 11 which is secured to turn with the door spindle 2. Cam 11, as

clearly seen in Fig. 1, is symmetrical about the longitudinal axis of the device and has a cam profile 12 for the "clockwise" roller 25 and a cam profile 12' for the "counterclockwise" roller 25'. Cam plate 11 is so disposed relative to door spindle 2 that when the door is in closed position, as in Fig. 1, the cam plate will be disposed substantially transversely or normal to the longitudinal axis of the mechanism, so that the clockwise cam profile 12 and the counterclockwise cam profile 12' are symmetrical with respect to the longitudinal axis.

Between the transverse bar 30 and the casing plate 8 are provided a regulating nut 26 on the "clockwise" rod 20 and a similar nut 26' on the "counterclockwise" rod 20', the rods being threaded, Fig. 2, for the nuts. Regulating nuts 26, 26' may be provided with radial holes 27, 27' to receive a pin, spanner wrench or other tool to facilitate turning thereof.

The clockwise coil spring 20 and the counterclockwise spring 20' are placed under the required amount of compression by regulating their respective lock nuts 22, 22', so that the necessary restraining force will be applied to the door to maintain it in closed position against wind rattling and other disturbances. In the closed position of the door, as shown in Fig. 1, the cam plate 11 is maintained in its transverse position as shown by the force exerted by the clockwise spring 10 and the counterclockwise spring 10' acting through their associated rod, links and roller, respectively 20, 23—24, 25, and 20', 23'—24', 25', upon the distal ends of the cam plate or lever 11. That is, any tendency to open the door in a clockwise direction will be met and counterbalanced by the compressed "clockwise" spring 10, which, acting on the lower (as shown in Fig. 1) distal end of cam lever 11, tends to turn the lever and the door in a counterclockwise direction; any tendency to open the door in a counterclockwise direction will be met and counterbalanced by the compressed "counterclockwise" spring 10' which, acting on the upper, Fig. 1, distal end of cam lever 11, tends to turn it and the door in a clockwise direction. Hence between the two opposing forces, the door is held firmly in its closed position.

To maintain the door precisely in its closed position, the springs 10, 10' must exert equal force on the cam lever 11, or rather, the same turning torque or moment. The regulating nuts 26, 26' are adjusted until the door is brought into the precise closed position. In this position, the compression springs 10, 10' will exert their maximum pressure on the respective regulating nuts 26, 26' which abut the transverse bar 30 of the housing. The surfaces 26—30 and 26'—30 therefore constitute the normal abutments of the rods 20, 21. This means that, in the closed position of the door, as in Fig. 1, the rollers 25, 25' will exert no force on cam plate 11. But if the door should be opened the slightest extent, in either direction, the springs 10, 10' will immediately exert a restraining force upon the door, through the rollers 25, 25' acting on cam plate 11.

But if a force greater than that exerted by the springs 10, 10' is applied to the door for the purpose of opening it, the force thus initially overcome will be the maximum. That is to say, the force (of springs 10, 10') required to be overcome in opening the door wide or to the fullest extent will decrease, rather than increase (as would be the case in devices heretofore made, as pointed out above). This decrease in restraining force

results from the construction of cam plate 11 and its two cam profiles 12, 12' which are so designed that the lever arm of the rollers 25, 25' is greatest in the closed position of the door, as in Fig. 1. It will be seen from this figure that the rollers 25, 25' are disposed at the outer or distal end of their respective cam profiles 12, 12', which means that the torque applied by their springs 10, 10' is at its maximum value. As the door continues to be opened, the roller which is called into play (depending upon the direction of door opening), will approach the inner or proximal end of its cam profile. For example, door 1A has been turned counterclockwise to a 45° open position. Opening of the door in this direction puts "counterclockwise" spring 10' into operation due to the coaction of cam profile 12' of cam plate 11 upon roller 25' of the rod 20', causing rod 20' to be pulled outward to the left in Fig. 3, thus compressing the spring 10'. It will be noted from Fig. 3 that the roller 25' is now disposed nearer to the proximal end of cam profile 12' and the center of pivot post 2, than in Fig. 1 (closed door position). Accordingly, the spring 10' will exert a reduced closing torque upon the door, because of the reduced lever arm of roller 25'.

Of course, in the opening turning of the door, the compression force of spring 10' (or 10) increases with the angle of door opening. But the improved device is designed so that the decrease in closing torque due to the reduced lever arm (at roller 25') is greater than the increase in the compression force of spring 10'. In certain instances, the increase in spring compression force and the decrease in lever arm may be made to substantially balance one another so that the closing torque remains substantially constant.

As the door is continued to be opened from its 45° opening position (Fig. 3) the roller, 25' or 25, approaches the proximal end of its respective cam profile 12', 12 until it rests at that end in the fully opened (90°) position of the door. This is shown in Fig. 4 wherein the door 1B has been turned clockwise to its fully opened (90°) position, thus putting clockwise spring 10 into play by pulling rod 20 outwardly. It will be noted that roller 25 is now at the inner or proximal end of its cam profile 12 (at which point the lever arm is at its minimum).

It will be observed that the cam plate 11 moves away from the roller of the spring assemblage that is not brought into play. For example, in the counterclockwise opening of door 1A in Fig. 3, the "counterclockwise" spring 10' comes into operation; cam profile 12 of cam plate 11 turns counterclockwise away from roller 25 (of the "clockwise" assemblage). In the clockwise opening of door 1B in Fig. 4, the "clockwise" spring 10 comes into operation; cam profile 12' turns clockwise away from roller 25' (of the "counterclockwise" assemblage).

The purpose in curving the links 23 (23'), 23' (23'') is to enable the distal portions of the links, i. e., adjacent to the rollers 25, 25', to clear the pivot post 2, in the fully opened door position, as clearly shown in Fig. 4.

The transverse bar 30 is spaced away from the regulating nuts 26, 26', see Fig. 1, so as to provide sufficient clearance for the respective ends of the transverse bar. The respective end of the transverse bar, when the door is turned from its closed position, abuts the associated regulating nut 26, 26'; this point of abutment becomes the pivot point for the bar. For example, when the door 1A is opened counterclockwise, Fig. 3, end 30C 75

of the transverse bar abuts regulating nut 26, the bar turning slightly on this point. When the door 1B is opened clockwise, Fig. 4, end 30CC of the transverse bar abuts regulating nut 26', the bar turning slightly on this point.

The transverse bar 30 is required for the purpose of associating the dampening means (next to be described) with the door closing means. If the dampening means were omitted, there would be no need for transverse bar 30 (nor is it required in the single-acting door, Fig. 5, subsequently described).

The dampening means comprises an oil cylinder 43 in which slides a piston 42 articulated to a piston rod 40, the other end portion of which is connected to a central point 41 of transverse bar 30. The inlet 44 to the oil cylinder has a check ball 45, while the outlet 46 has a regulating screw 47. On the pivot post 2 is secured a heart-shaped cam 6 which engages the distal (left in the figures) end of piston rod 40.

When the door is opened, for example, counterclockwise, Fig. 3, the turning of the transverse bar 30 (about its end 30C in Fig. 3; or it may be its end 30CC in Fig. 4) causes (in either case, Fig. 3 or Fig. 4) an outward movement—to the left—of piston rod 40. This leftward or outward movement of the piston rod is the suction stroke of piston 42, during which cylinder 43 takes in oil through inlet 44. The heart-shaped cam 6 turns with the pivot post 2, thus getting out of the way of the left end of piston rod 40, see Fig. 3 and also Fig. 4. When, however, the door is being closed, in the example, turned clockwise in Fig. 3, the heart-shaped cam 6 pushes against the end of piston rod 40 and forces it rightwardly. Rightward movement of piston rod 40 and piston 42 is resisted and slowed down by the escape of oil through restricted outlet 46.

The improved door closing and checking device, explained in Figs. 1 to 4, with reference to a double-acting door, may be applied to a single-acting door, as in Fig. 5, which happens to be for a door which opens in a counterclockwise direction. The parts are similar to those associated with "counterclockwise" spring of the double-acting door of Figs. 1-4 and are similarly designated, with the following exceptions. The cam plate 11x comprises only that half of cam plate 11, Figs. 1-4, which has the "counterclockwise" cam profile 12'. No transverse bar (30, Figs. 1-4) is required and no dampening cam (such as 6, Figs. 1-4) is secured to the pivot post. Instead, the piston 42x of dampening cylinder 43x is secured directly to the rod 20'.

I claim:

1. A device of the class described for a door having a pivot post, comprising, in combination, a housing having a plate disposed transversely of the longitudinal axis of the housing and provided with openings, a pair of rods disposed on either side of said longitudinal axis and clearing through said plate openings, and provided with lock nuts at one end thereof, a cam plate secured to said pivot post having a pair of cam profiles symmetrically disposed on either side of said longitudinal axis, a pair of links articulated to respective ones of said rods, a pair of rollers disposed at the distal end of said links and seated in respective ones of said cam profiles, regulating nuts adjustably disposed on respective ones of said rods at the side of said housing plate facing said link articulations, a pair of compression springs disposed about respective ones of

said rods and interposed between the opposite side of the housing plate and said lock nuts for urging said pair of rods in a direction to abut their said regulating nuts against the housing plate, the lock nuts being adjusted to predetermine the compressive force exerted upon the rods, and the regulating nuts being adjusted to position said rollers relative to their respective cam profiles to maintain the door in precise closed position by the restraint imposed by the respective compression springs.

2. A door device of the class described, comprising, in combination, a housing, a pair of rods disposed on either side of the longitudinal axis of said housing, and provided with lock nuts at one end thereof, a cam plate secured to turn with the door having a pair of cam profiles symmetrically disposed on either side of said longitudinal axis, a pair of links articulated to respective ones of said rods, a pair of rollers disposed at the distal end of said links and seated in respective ones of said cam profiles, abutments secured to said housing, regulating nuts adjustably disposed on respective ones of said rods at the side of said abutments facing said link articulations, a pair of compression springs disposed about respective ones of said rods and interposed between the opposite side of the abutments and said lock nuts for urging said pair of rods in a direction to abut their said regulating nuts against the abutments, the lock nuts being adjusted to predetermine the compressive force exerted upon the rods, and the regulating nuts being adjusted to position said rollers relative to their respective cam profiles to maintain the door in precise closed position by the restraint imposed by the respective compression springs.

3. A door device of the class described, comprising, in combination, a housing, a pair of rods disposed on either side of the longitudinal axis of said housing, a cam plate secured to turn with the door, having a pair of cam profiles symmetrically disposed on either side of said longitudinal axis, a pair of links articulated to respective ones of said rods, a pair of rollers disposed at the distal end of said links and seated in respective ones of said cam profiles, abutments secured to said housing, regulating nuts adjustably disposed on respective ones of said rods at the side of said abutments facing said link articulations, a pair of compression springs disposed about respective ones of said rods and abutting the opposite side of the abutments for urging said pair of rods in a direction to abut their said regulating nuts against the abutment, the regulating nuts being adjusted to position said rollers relative to their respective cam profiles to maintain the door in precise closed position by the restraint imposed by the respective compression springs.

4. A door device of the class described, comprising, in combination, a housing having an abutment, a rod disposed longitudinally of the housing and provided with a lock nut at one end thereof, a cam plate secured to turn with the door, a link articulated to said rod, a roller disposed at the distal end of said link and coacting with said cam, a regulating nut adjustably disposed on said rod at the side of said abutment facing said link articulation of the rod, a compression spring disposed about said rod and interposed between the opposite side of the abutment and said lock nut for urging said rod in a direction to abut its said regulating nut against the abutment, the lock nut being adjusted to predetermine the compressive force exerted upon the rod, and the regu-

lating nut being adjusted to position said roller relative to the cam to maintain the door in precise closed position by the restraint imposed by the compression spring.

5. A door device of the class described, comprising, in combination, a housing, a pair of rods disposed on either side of the longitudinal axis of said housing, a cam plate secured to turn with the door, having a pair of cam profiles symmetrically disposed on either side of said longitudinal axis, a pair of links articulated to respective ones of said rods, a pair of rollers disposed at the distal end of said links and seated in respective ones of said cam profiles, abutments secured to said housing, regulating nuts adjustably disposed on respective ones of said rods at the side of said abutments facing said link articulations, a pair of compression springs disposed about respective ones of said rods and abutting the opposite side of the abutments for urging said pair of rods in a direction to abut their said regulating nuts against the abutment, a bar disposed transversely of said casing axis and operatively connected to said pair of rods at their said link articulations, and a rod disposed centrally of the housing and articulated at the medial point of said transverse bar, whereby turning of the door in either direction causes a movement of the central rod in the same direction.

6. The combination according to claim 5 wherein in the adjacent edge of said transverse bar is spaced from said abutments to provide clearance for turning of one end of the transverse bar when the other end is moved away from the abutment by said cam.

7. The combination according to claim 5 further provided with a dampening means including an oil cylinder and a piston, said central rod being operatively connected to the piston.

8. A door device of the class described, comprising, in combination, a housing having an abutment, a rod disposed longitudinally of the housing and provided with a lock nut at one end thereof, a cam plate secured to turn with the door, a link articulated to said rod, a roller disposed at the distal end of said link and coacting with said cam, a regulating nut adjustably disposed on said rod at the side of said abutment facing said link articulations of the rods, a compression spring disposed about said rod and interposed between the opposite side of the abutment and said lock nut for urging said rod in a direction to abut its said regulating nut against the abutment, and a dampening means including an oil cylinder and a piston, the end of said rod being operatively connected to the piston.

9. A closing and checking device for a door having a pivot post, comprising, in combination, a housing, a pair of rods disposed on either side of the longitudinal axis of the housing, a cam plate secured to said pivot post having a pair of cam profiles symmetrically disposed on either side of said longitudinal axis, a pair of links articulated to respective ones of said rods, a pair of rollers disposed at the distal end of said links and seated in respective ones of said cam profiles, a pair of compression springs disposed about respective ones of said rods for urging the rods in a direction to press their respective rollers in engagement with said cam profiles.

10. A closing and checking device for a door having a pivot post, comprising, in combination, a housing, a pair of rods disposed on either side of the longitudinal axis of the housing, a cam plate secured to said pivot post having a pair of cam

profiles symmetrically disposed on either side of said longitudinal axis, a pair of links articulated to respective ones of said rods, a pair of rollers disposed at the distal end of said links and seated in respective ones of said cam profiles, a pair of compression springs disposed about respective ones of said rods for urging the rods in a direction to press their respective rollers in engagement with said cam profiles, a bar disposed transversely of said housing axis and operatively connected to said pair of rods at their said link articulations, abutments secured to the housing, and a rod disposed centrally of the housing and articulated at the medial point of said transverse bar, one end of said bar engaging one abutment when the other end of the bar is moved by said cam, whereby the bar is turned to move said central rod in the same direction irrespective of the direction of door opening.

11. A closing and checking device for a door having a pivot post, comprising, in combination, a housing, a pair of rods disposed on either side of the longitudinal axis, of the housing, a cam plate secured to said pivot post having a pair of cam profiles symmetrically disposed on either side of said longitudinal axis, a pair of links articulated to respective ones of said rods, a pair of rollers disposed at the distal end of said links and seated in respective ones of said cam profiles, a pair of compression springs disposed about respective ones of said rods for urging the rods in a direction to press their respective rollers in engagement with said cam profiles, a bar disposed transversely of said housing axis and operatively connected to said pair of rods at their said link articulations, dampening means including a piston rod, said rod being disposed on said housing axis and articulated centrally to said transverse bar, whereby opening of the

door in either direction will move the piston rod in one direction, and cam means secured to said pivot post for moving the piston rod in the opposite direction.

- 5 12. A closing device for a door having a pivot post, comprising, in combination, a housing, a pair of rods disposed on either side of the longitudinal axis of the housing, a cam plate secured to said pivot post having a pair of cam profiles symmetrically disposed on either side of said longitudinal axis, a pair of links articulated to respective ones of said rods, a pair of rollers disposed at the distal ends of said links and cooperative with respective ones of said cam profiles,
- 10 13. and spring means associated with said rods for pressing their respective rollers into engagement with the respective cam profiles, whereby a torque is imposed upon said cam tending to close the door, each of said cam profiles being adapted to move its cooperative roller towards said pivot post whereby the moment arm is reduced to decrease said closing torque.
